UNITED STATES PATENT OFFICE.

EDMOND BOUCHANE, OF PITTSFIELD, MASSACHUSETTS.

ICE-CUTTER.

1,224,840.

Specification of Letters Patent.

Patented May 1, 1917.

Application filed December 5, 1916. Serial No. 135,221.

To all whom it may concern:

Be it known that I, EDMOND BOUCHANE, a citizen of the United States, residing at Pittsfield, in the county of Berkshire and State of Massachusetts, have invented new and useful Improvements in Ice-Cutters, of which the following is a specification.

The present invention contemplates the production of a track-cleaner adapted for 10 cleaning snow and ice from car tracks and so connected, preferably with a street railway car or like wheeled vehicle, whereby the cutting disks will be directly driven by the propelling power of the car.

15 The primary object of the invention resides in the provision of a track cleaner of the above stated character wherein use is made of a driven shaft on which the cutting disks are disposed and arranged at an angle, 20 whereby after the snow or ice is cut or loosened the cutting disks will further perform the operation of throwing the snow to one side of the line of travel of the car.

To this end, use is made of a hanger supported from the car, a frame adapted for a vertical movement in said hanger, a driven shaft journaled in the lower portion of the frame on which are disposed said cutting disks in the manner above stated, and a lever 30 fulcrumed to said frame for performing the raising or lowering operations thereof.

With the above and other objects in view, the invention consists in the novel features, details of construction and combination of 35 parts which will hereinafter be more fully set forth, illustrated in the accompanying drawing and pointed out in the appended claims.

Figure 1 is a side elevation of a car 40 partly in section showing my device attached thereto;

Fig. 2 is a perspective view of the device removed from the car;

Fig. 3 is a bottom plan view;

45 Fig. 4 is a section taken on line 4—4 of Fig. 3.

Referring more particularly to the accompanying drawing, in which like characters of reference refer to corresponding parts in 50 the several views, the character 5 denotes generally the track cleaner attached to the front portion of a wheeled vehicle 6, which in this particular instance is shown as constituting a motor car. A hanger 7, of U-shaped form, is utilized for supporting and suspending the track cleaner from the front

portion of the wheeled vehicle 6 and the limbs 8 of said hanger are arranged in spaced vertical plane with one another, and are provided with an arcuate slot 9. Journaled in the bearings 10 of the limbs and transversely of the hanger 7 for rotary movement, is a driving shaft 11 having its extremities 12 projecting beyond the limbs 8 of the hanger. A gear 13 is supported 60 upon each of the extremities 12 of the driving shaft and defined thereon and between the nuts 14, while carried by one of the extremities 12 is a pulley 15, which is geared up with the front axle of the wheeled vehicle 70 6 through the medium of a belt 16.

Journalized in the lower extremities of the limbs 25 of the movable frame 23 is a driven shaft 26, having the opposite extremities thereof arranged in the arcuate slots 9 of the 75 hanger and extending beyond the outer faces of said hanger as at 27. The protruding extremities 27 of the protruding shaft 26 are likewise provided with pinions 28 adapted to mesh at all times with the gears 13 of 80 the driving shaft 11. Thus upon the driving of the shaft 11 it will in turn rotate the driven shaft 26. The rotation of this driven shaft 26 will cause the revolution of the plurality of cutting disks 29 mounted thereon, 85 whereby upon the operation of the lever 21 in an outward direction, will lower the frame 23 and bring the disks in contact with snow and ice packed or lodged between the rails for the express purpose of cutting or 90 loosening the same. After the snow and ice is cut through the influence of the serrated edges 30 of the cutting disks, the said cutting disks will perform the function of throwing the snow or ice to one side of the 95 line of travel of the car, due to the fact that I have shown these disks as arranged at an angle upon the driven shaft 26. It is further obvious that by the employment of the arcuate slots 9 and the manner of mounting 100 the driven shaft therein it will permit of the cutting disks being brought into engagement with the surface to be cut. It will, of course, be understood that the bar 15 is utilized in the raising or lowering actions of the frame 105 23 and is manipulated by grasping the handle 30 thereof. After the proper adjustment of the frame 23 is obtained, the teeth 31 of the rack bar are brought into engagement with one of the walls of the opening 32 110 by the tension of the spring 33, the latter being secured to the plate 34.

From the foregoing description, taken in connection with the accompanying drawing, the advantages of construction and the method of operation will be readily apparent to those skilled in the art to which the invention relates, and while I have described the principles of operation of the invention, together with the device which I now consider to be the best embodiment thereof, I desire to have it understood that the device shown is merely illustrative and that such changes may be made as are within the scope of the appended claims.

What is claimed as new, is:

- 15 1. A track clearer embodying in combination with a hanger provided with a pair of alined arcuate slots, a driving shaft journaled in said hanger, a pulley on said shaft, of a frame mounted in said hanger for vertical movement, a driven shaft journaled in said frame and protruding through the arcuate slots of said hanger, means for driving the former mentioned shaft, and a series of cutting disks on said driven shaft.
- 20 2. A track clearer embodying in combination with a hanger provided with a pair of alined arcuate slots, a driving shaft journaled in said hanger, a pulley on said shaft, of a frame mounted in said hanger for vertical movement, a driven shaft journaled in said frame and protruding through the arcuate slots of said hanger, means for driving the former mentioned shaft, and a series of cutting disks on said driven shaft, said disks being arranged at an angle substantially as and for the purpose specified.
- 25 3. A track clearer, comprising in combination with a hanger provided with a pair of transversely alined arcuate slots, a driving

shaft journaled in said hanger, gears on said shaft, of a movable frame mounted in said hanger and having a portion thereof protruding through a slot formed in the hanger, an operating lever connected with the protruding portion of the frame for effecting the vertical movement of the frame, a driven shaft journaled in the lower extremities of the frame and protruding through the arcuate slots of the hanger, gears on the protruding extremities of the driven shaft and adapted to mesh with the gears of the driving shaft, means for imparting movement to said driving shaft, and a series of spaced cutting elements on the driven shaft.

4. A track clearer, comprising in combination with a hanger provided with a pair of transversely alined arcuate slots, a driving shaft journaled in said hanger, gears on said shaft, of a movable frame mounted in said hanger and having a portion thereof protruding through a slot formed in the hanger, an operating lever connected with the protruding portion of the frame for effecting the vertical movement of the frame, a driven shaft journaled in the lower extremities of the frame and protruding through the arcuate slots of the hanger, gears on the protruding extremities of the driven shaft and adapted to mesh with the gears of the driving shaft, means for imparting movement to said driving shaft, and a series of spaced cutting elements on the driven shaft, said cutting elements being arranged at an angle, substantially as and for the purpose specified.

75 In testimony whereof I affix my signature.

EDMOND BOUCHANE.
